CLAIM

The ornamental design for a combination hoe and cultivator as shown and described.

DESCRIPTION

FIG. 1 is a front and left side perspective view of a combination hoe and cultivator showing my design;

FIG. 2 is a rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is an exploded perspective view showing the three segments of the combination hoe and cultivator in a separated state.

The broken lines in the drawings depicting portions of the combination hoe and cultivator that form no part of the claimed design.
